UNITED STATES PATENT OFFICE.

WILLIAM C. H. NOBLE, OF LOS ANGELES, CALIFORNIA.

MEANS FOR HUMIDIFYING AND WASHING AIR.

1,100,144.

Specification of Letters Patent. Patented June 16, 1914.

Application filed September 2, 1913. Serial No. 787,634.

To all whom it may concern:

Be it known that I, WILLIAM C. H. NOBLE, a citizen of the United States, residing at Los Angeles, in the county of Los Angeles and State of California, have invented a new and useful Means for Humidifying and Washing Air, of which the following is a specification.

This invention relates to means for supplying moisture to air and at the same time, removing from the air any suspended matter such as dust, and the main object of the invention is to provide means for performing these operations in the most economical and effective manner, and with a minimum of moving parts.

Other objects of the invention will appear hereinafter.

The accompanying drawings illustrate a machine embodying my invention, and referring thereto:

Figure 1 is a vertical longitudinal section of the machine. Fig. 2 is a transverse section on line x^2-x^2 , Fig. 1. Fig. 3 is a detailed section showing the construction of the filter members. Fig. 4 is a plan view of the outer filter members. Fig. 5 is a transverse section through a portion of the casing, showing the filter members in section. Fig. 6 is a detail section partly in elevation of the water distributing means.

The machine comprises a casing or shell 1, a rotary fan 2, water distributing means 3 for supplying water to said fan, and filtering means interposed in the path of the air passing from said fan to perform the humidifying and washing operations thereon.

The casing 1 may be of any suitable form being, for example, an upright sheet metal casing, rectangular in cross section at its lower portion, and having at one side an inlet 5 through which air passes from the outside to the interior of the casing, and said casing having at its upper portion at one end thereof, an outlet 6 through which the air is delivered to any suitable pipe for conveying it to any desired place or places. The side of the casing opposite the said outlet pipe 6 is preferably rounded as shown at 7, so as to direct the air to the outlet. The bottom portion of the casing is formed as a watertight tank indicated at 8, to receive a body of water indicated at 9, and to collect the water draining or dripping from the filtering means, as hereinafter set forth. Water is supplied to this tank or water re-

ceiving portion 8 of the casing by a water supply pipe indicated at 10, and an overflow or outlet 11 is provided for carrying off the water when it rises above a definite level, so as to maintain a constant level in the said portion of the casing. A drain pipe 12 normally closed by a valve 13 is provided to drain out the contents of the water tank 8 when required.

The fan 2 is carried by a rotary shaft 14 mounted in bearings 15 on a frame or standard 16, said shaft carrying a driving pulley 17 whereby power is applied thereto to rotate the fan 2. The fan 2 may be of any suitable construction, being for example, composed of a series of blades or vanes 17 carried by a spider 18 mounted on the shaft 14, said blades being preferably concaved or cupped on their forward faces.

The water distributing means comprises tubular arms or pipes 3 communicating with a bore 19 in the shaft 14 and having nozzles 20 at their outer extremities to discharge water into the space within the fan blades 17 and onto said fan blades. Two series of said tubular arms or pipes 3 may be provided as shown, in order to effect better distribution of the water onto the fan blades. Water is supplied to the tubular shaft 14 by a pipe 21 communicating with any suitable portion of water supply, for example, with the outlet of a pump not shown, whose inlet is connected to a pipe 22 communicating with the water tank 8 aforesaid.

In the casing 1 above the water tank 8 are provided a plurality of intercepting plates 23 and 24 perforated as shown at 25, said perforations being staggered in the respective plates, the function of these plates being to prevent the lifting or entraining of the water in the bottom of the casing 1 by reason of the rapid rotary motion of the air in said casing, while permitting drainage of water from the filtering means to the bottom of the casing. Above said intercepting plates 23 and 24 and around the fan 2, I provide a plurality of filtering devices. The inner filtering devices consist preferably of a series of wire screens 26 supported by cross bars 27 extending across the casing 1 and the outer filtering and eliminating means consisting preferably of a series of perforated plates 30, 31 and 32 supported by cross bars 33 extending across the casing 1. The said inner filtering devices are preferably closer to the fan at their lower portions and

diverge from the fan at their upper portions, so that the air space between the fan and inner filtering devices increases in area on the ascending side of the fan in the direction 5 of motion of the fan. For this purpose the portion of the inner filtering devices from the lower to the upper part thereof on the ascending side of the fan is preferably spiral, the portions on the opposite side of 10 the fan being formed with horizontal and vertical parts 34 and 35, and a deflector 36 is arranged in the angle between said horizontal vertical parts so as to obstruct and arrest the rotary movement of the air and 15 deflect the air upwardly through the filtering devices toward the outlet 6. The outer filtering devices are arranged in similar manner to the inner filtering devices and are provided with perforations 38 and with fins 20 or projections 39 adjacent to said perforations to increase the acting surface and to more effectively intercept the air passing therethrough. These fins or projections 39 are preferably formed by bending up the 25 portions of the metal cut out from the plates in forming the perforations 38 and in order to increase the baffling and intercepting effect, the fins 39 on the inner plates 30 and 31 are turned inwardly and the fins 39 on 30 the outer plate are turned outwardly as shown in Fig. 3. The edges of these fins 39 and of the openings 38 operate to separate or eliminate any drops or particles of water entrained with the air. The devices 35 30, 31 and 32, thus serve as eliminators for unevaporated entrained water in addition to their functions of filtering and humidification.

The operation is as follows: Water having 40 been supplied to the tank portion 8 of the casing, as indicated at 9, the shaft 14 is set in rotation, causing the fan 2 to revolve and to force the air outwardly from the fan by centrifugal action, the air being drawn in 45 through inlet 5 and passing through the blades 2 and being set in rotative action thereby and delivered through the filtering devices to the outlet 6. At the same time, water is supplied through the pipe 21 and 50 tubular shaft 14 to the water distributing pipes 3 and nozzles 20 which discharge the water onto the rapidly moving fan blades 17 by which the water is broken up so that it passes along the air in the form of a more 55 or less finely divided spray. The fan blades being continually moved in this manner act to some extent as intercepting surfaces, catching any dust and causing it to be caught by the water, but the main washing 60 action as well as the humidification of the air is effected by the filtering devices, consisting of the wire screens 26 and the intercepting plates 30, 31 and 32 which present an enormous surface which is continually 65 wetted by the passage of the water there-

through and which continually intercept and baffles the current of air and bringing it into effective contact with the water, the projections 39 of the intercepting plates being especially important in this intercepting and 70 baffling action. The water passing along with the air is in part taken up by the air, humidifying the same, the rest of it collecting on the filtering devices and draining therefrom through the intercepting plates 75 23 and 24 into the body of water 9 into which the water overflows into pipe 11 or is repumped to the water distributing means by suitable pumping devices.

The outer filtering devices 30, 31 and 32 80 have the further function of eliminating any excess of moisture that is taken up by the air. It is desirable that the humidity of the air be maintained at or about a certain value, in most cases, about 60% relative humidity, 85 and any excess of humidity over this amount is objectionable as it involves waste of heat, liability to deposition of dew on cooling. In passing through the first set of filtering devices the air will in general, attain close to 90 saturation, and as this air passes over the edges of the punched out fins or projections 39, the small drops or particles of water that are being carried along by the air are caught by said edges and the air thereby relieved of the excess humidity, leaving only that portion of the entrained water that has been evaporated and taken up by the air. The small spheroidal drops that would be carried by mere velocity without having 95 been evaporated are eliminated and the air is left in a condition running from 40% or 60% or 70% of saturation, and in such shape that it can be readily made use of for 100 ventilating.

What I claim is:

1. An air humidifying and washing device, comprising a casing having an inlet and an outlet, a rotatably mounted shaft having a portion extending within the casing, a fan carried by said shaft and comprising a circular series of blades, a plurality of water distributing nozzles carried by said shaft, said shaft being tubular and provided with means for supplying water therethrough to said nozzles, said nozzles being located within the circular series of fan blades to supply water thereto, and filtering devices located in fixed position within the casing between the fan and the outlet of the 115 casing.

2. An air humidifying and washing device, comprising a casing having an inlet in its side and an outlet at its upper portion, a fan rotatably mounted in said casing and 120 provided with a series of circularly arranged blades, the said inlet of the casing opening into the space within said blades, water distributing means for supplying water at the inner side of said blades, and a perforated 125 130

screen extending across the casing from side to side, and completely surrounding said fan.

3. An air humidifying and washing device, comprising a casing having an inlet in its side and an outlet at its upper portion, a fan rotatably mounted in said casing and provided with a series of circularly arranged blades, the said inlet of the casing opening into the space within said blades, water distributing means for supplying water at the inner side of said blades, and a plurality of perforated screens extending across the casing from side to side, and completely surrounding the same, the outermost of said screens being provided with projections serving for elimination of water from the air passing therethrough.

4. An air humidifying and washing device, comprising a casing having an inlet in its side and an outlet at its upper portion, a fan rotatably mounted in said casing and provided with a series of circularly arranged blades, the said inlet of the casing opening into the space within said blades, water distributing means for supplying water at the inner side of said blades, a plurality of perforated screens extending across the casing from side to side, and completely surrounding the same, the outermost of said screens

being provided with projections serving for 30 elimination of water from the air passing therethrough, and a deflector between said screen and fan for deflecting the air from the fan toward the outlet of the casing.

5. A humidifying and washing device for 35 air, comprising a casing having an inlet in its side and an outlet at its upper end portion and adapted to contain a body of water in its lower portion, a fan rotatably mounted in said casing adjacent to said inlet, means 40 for pumping water from the lower part of said casing and distributing it onto said fan, a screen extending around said fan between said fan and said outlet, and a perforated plate extending between said screen and the 45 said body of water in the lower portion of the casing to permit water from the screen to drip to said body of water, but to prevent water being taken up from said body of water by the motion of air produced by the 50 fan.

In testimony whereof, I have hereunto set my hand at Los Angeles, California this 26th day of August, 1913.

WILLIAM C. H. NOBLE.
